UNITED STATES PATENT OFFICE.

HORACE M. HOOVER, OF PERRYSBURG, OHIO.

WOOD-FIBER MACHINE.

No. 901,969.

Specification of Letters Patent.

Patented Oct. 27, 1908.

Application filed February 12, 1906. Serial No. 300,623.

To all whom it may concern:

Be it known that I, HORACE M. HOOVER, a citizen of the United States, residing at Perrysburg, in the county of Wood and State of Ohio, have invented certain new and useful Improvements in Wood-Fiber Machines; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to that class of wood working machines in which a gang of saws, forming a cutter-head, operating upon the surface of a bolt or log of wood reduces the log to a fiber of greater or less fineness.

20 The object of my invention is to provide a simple and efficient means for presenting and feeding the log or bolt or a series of logs and bolts to the cutter-head or a series of cutter-heads.

25 I attain these objects by means of the devices and arrangement of parts hereinafter described and shown, and illustrated in the accompanying drawings, made part hereof, in which,—

30 Figure 1 is a side-elevation of my device, with part of the center pillar broken away to show its interior arrangement; Fig. 2, a side-elevation of the same, seen from the side opposite that shown in Fig. 1; Fig. 3, a side-elevation partly in section of the detachable dog, hereinafter referred to, designed to engage the ends of the bolt or log to be supported and operated upon; Fig. 4, a top-plan view of the same; Fig. 5, a side-elevation of 35 another dog, hereinafter referred to, designed to engage the sides of the bolt or log to be operated upon; Fig. 6, a top-plan view of the same; Fig. 7, a part of the gearing, hereinafter referred to, on an enlarged scale, showing a modified form of construction; Fig. 8, a top-plan view of a segment of the log or bolt carriage hereinafter referred to, and Fig. 9, a perspective view of the feed-screw and its threaded nut or bracket hereinafter referred to.

Like numerals and letters of reference indicate like parts throughout the drawings.

In the drawings, 1 is a stout base or frame rigidly supporting at its middle a strong pillar-block 2 from which springs vertically a hollow-pillar 3 having at opposite sides lon-

gitudinal slots 3^a. This pillar has a vertically movable collar 3^b, also a head 3^c. These lugs are designed and arranged to be connected with guy-wires or ropes to steady the pillar in its vertical position. S is a heavy screw supported vertically within and arranged axially of the pillar 3. This screw carries a nut or bracket N from opposite sides of which project arms N', the extremities of which pass through the slots 3^a in the pillar 3. These extremities support the collar 3^b, which is provided with shallow notches on its under side which engage the extremities of the arms N' and prevent the collar 3^b from revolving.

4 is a circular carriage or platform having around its periphery cogs 4^a, and having central hub 4^b which loosely embraces the pillar 3. Secured to near the top of the pillar is a stout arm or bracket 5 projecting outwardly and curved downwardly. In the outer extremity of this arm is journaled, as at 5^a, a vertically elongated pinion 6 which engages and drives the teeth 4^a of the carriage 4. At bottom, the shaft 6^a, of the pinion 6, is provided with a friction-disk 7. This shaft is also provided with a pinion 8 fixed upon said shaft. Pinion 8 is engaged with and is adapted to drive a friction-wheel 8^a or disk 9 having a toothed periphery and supported in a cross-arm of the frame, as at 9^a. (See Figs. 1 and 2.) 10 is a shaft on which is a friction-wheel 11 movable longitudinally of the shaft but revoluble therewith. The outer extremity of the shaft 10 may be raised and lowered by means of lever 12, fulcrumed, as at 13, and controlled by a screw 14 vertically movable in fixed nut 15, supported in bracket 16, and operated by hand-crank 17. At its inner end shaft 10 has sufficient play to permit the outer end of the shaft to be raised or lowered slightly, thus bringing the friction-wheel 11 in contact either with the upper friction-wheel 9 or the lower friction-wheel 7 as the case may be.

In Fig. 7 I have shown the friction-disk 9 as internally toothed, as at 9^a, and driven by an internal spur-cog 9^b on shaft 9^c which carries another spur-gear 9^d engaged with the spur-gear 8. This modification is provided for reducing the motion of disk 9 in certain kinds of work and upon certain kinds of wood.

18 is the driving pulley upon the outer end of the shaft of the cutter-head 19. This

shaft is belted, as at 20, to pulley 21 on counter-shaft 22 which carries a friction-wheel 23. This friction-wheel revolves with but is longitudinally movable upon the shaft 22. I have shown means for the longitudinal adjustment of the friction-wheels 11 and 23 upon their respective shafts comprising rack-arms 24 loosely engaged with the hubs of these friction-wheels, each rack-arm being engaged by a pinion 25. By means of a hand-crank which may be temporarily placed upon the shaft of either of the pinions 25, either of the racks 24 may be caused to travel, thus carrying its attached friction-wheel into the desired position on its shaft. On the inner end of the shaft 10 is a beveled pinion 26 which drives a corresponding beveled pinion 27 fixed to the end of a short shaft upon the opposite end of which is a like beveled pinion 28 which in turn drives a beveled pinion 29 secured to the lower end of the screw S.

The operation of my device thus far described is as follows: The friction-wheels 11 and 23 are first adjusted upon their respective shafts in such relation to the friction-disk 7 that the proper speed will be given by the wheel 23 to the disk 7 and by the disk 7, in turn to the wheel 11. Now assuming that the shaft 10 is raised so that the wheel 11 is in contact with the friction-wheel 9 near its center, and that the driving pulley is in motion, the carrier or table 4 will be given two motions, viz., a rotary motion on its axis, and a vertical motion, bodily, upon its supporting pillar 3. The rotary motion is obtained through pulley 18, belt 20, pulley 21, shaft 22, friction-wheel 23, friction-disk 7, shaft 6^a, and elongated pinion 6, engaging the teeth 4^a of the carriage 4. The teeth 4^a of the table or carriage 4 will at all times engage the teeth of the long pinion 6 no matter how the carriage may be raised or lowered on its shaft. The vertical motion is obtained through shaft 6^a, (which is driven as just described,) pinion 8 engaging the teeth on friction-wheel 9, friction-wheel 11 in contact with said wheel 9, shaft 10, train of gears 26—27—28 and 29 which drives the screw S. The rotation of the screw causes the nut N and the carriage or table 4 resting upon the sleeve 3^b to slowly descend. When it is desired that the table or carriage shall ascend, the shaft 10 by means of crank 17 and lever 12 is lowered so that the wheel 11 rests upon the top of friction-wheel 7. The motion of wheel 11 is now reversed and through the train of gearing above described, the motion of the screw is reversed and the carriage or table is caused to ascend. As the wheel 11 rests upon the wheel 7, and near its margin, the friction contact causes the wheel to revolve more rapidly than when it is in contact with the wheel 9 near its center. Thus the raising of the carriage is accomplished

quickly while its lowering proceeds quite slowly. It will be seen that the rate of speed of raising and lowering the carriage is regulated by the relation of the driven friction-wheel with the axis of its driving friction-wheel.

Through the carriage or platform 4 are equi-distant openings O, of such dimensions as to facilitate the handling of the bolts or logs to be operated upon as well as the dogs used to support the work. In the example shown in the drawings, there are four of these openings arranged 90° apart. At each of these openings are dogs arranged to support between them the bolt or log to be operated upon. These dogs are designed to engage the ends and the sides of the log or bolt at or near its top so that the log will be suspended between the dogs and so that the logs may be almost entirely reduced without the dogs coming in contact with the saws of the cutter-head.

The dog-mechanism for engaging the ends of the bolt or log as above indicated consists of a frame or housing 30, the sides and one end of which are composed of channel-bars. At one end of the housing is a bottom cross-piece 30^a which projects beyond the end. To the under side of this cross-piece is rigidly secured a dog 30^b, its point projecting inwardly. At the opposite end of the housing is a head-block 30^c arranged to slide in the housing. To the under side of the head-block is secured another dog 30^d with its point projecting inwardly. The movable dog 30^d is actuated by means of a lever 30^e fulcrumed between the sides of the housing, as at 30^f, and having pivoted thereto, as at 30^g, a rack-bar 30^h. This rack-bar rests upon the top of the sliding head 30^c with the teeth uppermost. Between lugs 30ⁱ projecting upwardly from the head 30^c is pivoted a double pawl 30^k, having a handle by means of which the pawl may be swung with either of its opposing teeth into engagement with the rack-bar. It will be seen that by the throw of the lever 30^e, the dog 30^d may be moved into or out of engagement with the end of the bolt or log indicated by dotted lines in Fig. 3, and that by the movement of the lever the block may be pressed endwise so that the fixed dog 30^b will be forced into engagement with the opposite end of the log. The housing and dogs here described are detachable from the carriage 4. The dogs 30^b and 30^d being engaged with the end of the block to be operated upon, as above described, the block and dogs are lifted into place and are secured upon the carriage as follows: At one end of the housing is a projecting bottom plate 30^l with a vertical hole through it. This plate is first passed through the hole O and slipped endwise so that the hole through the end plate will slip over an upwardly projecting lug 30^m. The projecting

end of the plate 30^a at the opposite end of the housing is slotted, as at 30^b, (see Fig. 4.) This end is pressed upwardly against the under side of the carriage 4 where it is engaged by a button 30^c which slips through the slot in the end-plate and which has a handle 30^d by means of which the button is thrown into or out of engagement with the housing 30.

To further secure the log or bolt in place, I provide a pair of dogs which engage the sides of the log or bolt near its top. These dogs may be constructed and operated as follows: 31—31 are a pair of brackets bolted or riveted at 32, (see Fig. 8,) to the top of the carriage 4. In these brackets are openings through which pass horizontally the ends of a pair of parallel rack-bars 33 having their teeth uppermost. To the bottom-side of each of these rack-bars is secured a dog 34, the two dogs opposing each other at opposite ends of the bar. Through the top of the brackets pass set-screws 35 which engage the rack-bars and securely hold them against movement. The rack-bars are operated by means of a lever passed between the upwardly projecting teeth on the bars as indicated by dotted lines in Fig. 6. After the log or bolt is secured and put in place by means of the end dogs, the side dogs are also moved into engagement with the sides of the log at its middle and the bars 33 are secured in place by means of the set-screws 35.

It will be understood without illustration that each of the openings of the carriage or table is provided with the dogs and mechanism for controlling the same here described.

The cutter-head 19 may consist of any usual or preferred construction. In my machine I prefer to use a plurality of cutter-heads, such as here described, disposed in the same horizontal plane. In the machine illustrated in the drawings there are two of these cutter-heads placed at a right-angle to each other, one of them being driven by an independent belt and pulley 37. (See Fig. 2.)

For the purpose of adjusting the two cutter-heads vertically I have mounted and journaled each cutter-head in a stout yoke or housing 38. This yoke or housing is vertically movable in ways 39, secured to the frame of the machine. 40 is a shaft, journaled in the frame of the machine, provided with cams 41 each of which has an arm 42 which is pivotally connected, as at 43, with the yoke or housing 38. Upon the outer end of the shaft 40 is a worm-wheel 44 engaged by a worm 45, the shaft of which is journaled in a bracket 45^a and is provided with a hand-crank 46. When the hand-crank is turned the worm-gear causes the shaft 40 to revolve and thus the cams on the shaft 40, through arms 42, cause the yoke or housing to ascend or descend according to the direction in which the hand-crank is turned. It will be seen

that the worm-gear 44—45 holds the shaft 40 in its cam and the connections with the yoke or housing at all times rigidly locked in position. This adjustment may be used to accommodate the wear of the cutters and to accommodate the varying depth of the successive cuts of the two or more cutter-heads. Other means of vertically adjusting the cutters will suggest themselves and I do not, therefore, limit this feature of my invention to the construction here shown.

The further operation of my device is as follows: Assuming that the logs or bolts of wood to be operated upon are secured, by means of the dogs, in position, to the carriage or table 40 as above described; that the table is revolving upon its axis and slowly descending upon the screw S, and that the cutter-heads are rapidly revolving upon their shafts. The bottom of the logs or bolts will now in succession come in contact with the tops of each of the cutter-heads, and at each revolution of the table a portion of the logs or bolts will be removed and reduced to fiber, the removed portion corresponding with the lead of the thread on the screw S.

Having described my invention, what I claim and desire to secure by Letters Patent, is—

1. In a wood-fiber machine, a cutting mechanism, a pillar, a carriage, means for rotating the carriage upon the pillar, means for moving the carriage upon the pillar toward and away from the cutting mechanism, and means for securing a log or bolt to the carriage in operative relation to the cutting mechanism.

2. In a wood-fiber machine, a frame, a cutting mechanism, a pillar, a carriage or table revolvably mounted on said pillar, means for securing a log or bolt to said carriage, a toothed gear at the margin of the carriage, an elongated pinion engaging the toothed gear, a screw-support for the carriage, and means for driving the pinion and the screw whereby said table is caused to revolve upon its axis and to reciprocate upon the pillar toward and away from the cutting mechanism.

3. In a wood-fiber machine, a cutter-head, a pillar, a carriage journaled upon the pillar, a screw in said pillar, connections between the screw and the carriage, and means for revolving the screw, the carriage and the cutter-head.

4. In a wood-fiber machine, a cutter-head, a revoluble carriage, a screw support therefor, a train of gearing adapted to drive said screw in either direction, and means for actuating said train rapidly in one direction and slowly in the other direction.

5. A wood-fiber machine comprising a base or frame, a series of cutter-heads journaled therein, and in radial relation to each other, a pillar, a carriage vertically and revolvably movable upon said pillar, means for se-

curing a series of logs or bolts to said carriage, means for feeding said carriage and its load slowly to the cutter-heads, and means for withdrawing said carriage rapidly from the cutter-heads.

6. In a wood-fiber machine, a carriage, means for revolving the carriage horizontally, mechanism for moving the carriage vertically, gearing in said mechanism for operating the same in opposite directions at different rates of speed, said mechanism including two friction-disks, a friction-wheel adjustable longitudinally upon its shaft and disposed intermediate said two friction-disks near the center of one and near the periphery of the other, and means for throwing said latter friction-wheel into or out of contact with either of said friction-disks.

7. In a wood-fiber machine, a yoke or housing, a cutter-head journaled therein, slides or ways for said yoke or housing, a worm-gear and connections intermediate the worm-gear and the yoke or housing whereby the yoke or housing may be reciprocated upon its ways, and whereby the yoke or housing may be locked in adjusted position.

8. In a wood-fiber machine, a series of cutter-heads, a carriage or table above said cutter-heads, means for securing a series of logs

or bolts beneath said carriage or table, means for revolving said carriage, means for feeding the carriage and its logs or bolts toward and away from the cutterheads, and dogs on the carriage or table for each log or bolt, adapted for engagement with said logs or bolts.

9. In a wood-fiber machine, a revoluble carriage having openings therethrough, at each opening a pair of dogs adapted for engagement with the ends of the log or bolt to be operated upon, and another pair of dogs adapted for engagement with the sides of such bolt combined with a cutting mechanism, means for rotating said carriage, and means for feeding said carriage toward and away from the cutting mechanism.

10. In a wood-fiber machine, a cutter, a rotary carriage, a frame, dogs upon the frame adapted to engage and support the bolt to be operated upon, and means for detachably engaging the frame with the carriage.

In testimony whereof I affix my signature in presence of two witnesses.

HORACE M. HOOVER.
